FOLDING DOOR

Angelo T. Garubo, Newark, N. J.

Application November 23, 1948, Serial No. 61,615

6 Claims. (Cl. 160—113)

1

The present invention relates to folding doors, partitions, and the like. More particularly, it relates to improvements in a folding-section portion of a wall, ceiling, or roof comprising means for communicating lateral displacement from one of a number of sections, for example, a section having a handle on it, to all of the others and for maintaining a parallel relationship between surfaces of the sections throughout the range of their lateral displacement.

It is known to the prior art to employ folding doors and partitions in situations where it would be inconvenient to control a single door or movable partition of the size required. A usual practice in such a situation has been to employ an ungainly arrangement comprising a plurality of doors hinged to one another edge-on-edge with one of them hinged to a wall of the large room in which it is employed. In such an arrangement there is ordinarily no means for causing synchronous folding or unfolding of the several doors and because of this fact they are difficult to manage and are easily damaged.

Another well known expedient is to use sliding partitions which can be moved out of the way into a space provided between two surfaces of a partition. The difficulty with such an arrangement is that it requires a special and expensive construction for that partition.

It is one object of the present invention to provide a folding-section door or the like having associated pantograph or lazy-tong means for communicating synchronous lateral displacement between a number of cooperating sections and for maintaining them in a parallel relationship throughout their displacement in either direction whereby they may be easily placed in an "open" condition with the sections compactly nested together or in a "closed" condition with the sections extended and disposed sequentially adjacent to one another edgewise.

While prior art folding doors have the disadvantages which have been explained herein, conventional swinging doors also have a number of disadvantages which it is the purpose of this invention to eliminate.

A principal disadvantage is that swinging doors inherently are prone to slamming, especially if they are spring-loaded. It is evident that the edge opposite the rotational axis of the door may, especially in a wide door, move with considerable velocity even though the angular rotation is at a low rate. For heavy and/or spring-loaded doors this has necessitated the use of expensive checks and energy-absorbing devices.

2

Therefore it is a further object of the present invention to provide a folding-section door of the kind described above which may be take the place of an ordinary swinging door of average size with its pantograph means for synchronously turning each of the sections so arranged that even when spring-loaded the door does not have the disadvantage of slamming or banging against the jamb.

It is a further object to provide a folding "door" of the kind in question which is suitable for overhead use in a ceiling or roof, as, for example, in a solarium roof.

It is a further object of the present invention to provide a folding-section door of the kind described above which is suitable for use as a garage door in which the sections extend horizontally and in which individual means such as springs are provided for balancing the weight of the respective sections so that there is little difference in the amount of energy for opening or closing the closure-portion.

Other objects, features and advantages of the present invention will be apparent to those skilled in the art from the following detailed description of illustrative embodiments of the invention and from the drawing in which:

Figure 1 is a front elevation of a folding-section door suitable for taking the place of an ordinary swinging door and having one element partially cut away to disclose the arrangement of other elements;

Figure 2 is a front elevation of a cut-off upper portion of the structure shown in Figure 1 illustrating the outward displacement of an apron element which is effected as the door is opened;

Figure 3 is a transverse sectional view of a fragmentary upper portion of the structure shown in Figure 1, the section being taken along the line 3—3 shown in Figure 1;

Figure 4 is a transverse sectional view of a fragmentary lower portion of the structure shown in Figure 1, the section being taken along the line 4—4 shown in Figure 1;

Figure 5 is a horizontal sectional view of the upper portion of the structure shown in Figure 1, the section being taken along the line 5—5 shown in Figure 1;

Figure 6 is a representation of a horizontal sectional view corresponding to that of Figure 5 which would be produced along the line 5—5 of Figure 1 if the folding door were in a partly opened condition;

Figure 7 is a representation of a horizontal sectional view corresponding to that of Figures 5

and 6 but which would be produced along the line 5—5 of Figure 1 if the folding door were in a fully opened condition; and

Figure 8 represents a horizontal sectional view corresponding to that of Figure 5 for a modified form of the embodiment of Figure 1, so modified that when the door is in its fully opened condition the sections are so co-extensive edge-to-edge that their respective front and back surfaces lie in the same two planes.

Figure 9 corresponds to a portion of Figure 3 and illustrates a modification including a spiral spring for holding a section either normally open or normally closed.

Fig. 10 corresponds to Fig. 9 and illustrates an arrangement for staggering the spiral springs for adjacent sections to prevent them from interfering with each other when the sections are nested together as in Fig. 7.

Figure 1 shows a door opening surrounded by a conventional casing 1. In the description herein the inner upright opposite surfaces of the casing will be referred to as the jambs and the inner top surface as the head jamb. At the bottom of the opening there is a saddle 2, which may be a conventional hard wood saddle modified to meet the requirements hereof. A suitable modification is most clearly shown in Figure 4. A channel or slot is cut in the top surface of the saddle along its long axis approximately midway between its edges. Since this slot is to serve as a pivot bearing and a guideway in preferred forms of the invention, it will be advantageous to line it with a metallic U-channel 3, which may be connected in the slot by any suitable means, such as a number of screws 4.

In the example shown in Figure 1, the folding door has four sections. Three of these, sections 5, 5a and 5b, are full-width sections, each of which is substantially at least as wide as $\frac{7}{8}$ of the width of the door opening. Each of the sections is preferably somewhat wider than this to provide overlap between adjacent sections. The fourth section which will be referred to as anchor section 6 is at least half as wide as the other sections. It is the only section which is turned without being laterally displaced as a whole, as the door is opened or shut and which is turned about an axis near to one of its edges, rather than midway between them. It is section 6 which determines the nesting position for the sections when the door is open. For this purpose, it is provided with a bottom pivot 7 and a top pivot 8 (which is concealed by the apron in Figure 1 but appears in Figures 5, 6, 7 and 8). If desired, hinges, not shown, may be used to assist in anchoring and supporting section 6. This will be especially advantageous, for example, for a garage door. However, pivots 7 and 8, in addition to anchoring section 6 and affording it a rotational axis, also play a part in a pantograph or lazy-tong linkage arrangement whereby its rotation is related to the rotation and displacement of the other sections. For this reason, where no great strain is to be imposed on the anchor section, it is convenient simply to employ top and bottom pivots as herein shown. The saddle channel and its metallic lining 3 do not extend all the way to the left jamb of frame 1 but terminate at a short distance therefrom. In a line with the axis of the channel and nearer to the left jamb than its termination, a socket is provided for anchor pin 7. This socket may be a hole bored in the saddle and lined with a sleeve

of metal. A corresponding socket is provided for anchor pin 8 in the head-jamb of frame 1.

Pivots 7 and 8, as well as other similar pivots to be described below, may be fastened to the ends of the respective sections in any suitable manner. For example, they may be formed with wood screw threads and screwed into the sections. However, in the example shown herein, the pivots are mechanically connected, e. g., welded, to shallow U-channels which in turn are fitted over and connected to the ends of the respective wood sections. This has been found suitable for a number of reasons. The channels provide a smooth surface for the end of the sections which is desirable in preference to the end-grain wood surfaces for smoothest operation of the inter-linkage arrangement shown in Figures 5, 6 and 7. In addition, the channels impart a finished appearance to the ends of the sections and strengthen them against warping. Each respective section, 5, 5a and 5b, has a bottom pivot, 9, 9a and 9b, and a top pivot 10, 10a and 10b. Except for the fact that they are fastened to sections 5, 5a and 5b in alignment with the respective center axes thereof instead of near to an edge, the bottom pivots 9, 9a, and 9b are similar to pivot 7. On the other hand, the top pivots, 10, 10a and 10b, differ from pivot 8 in one further respect. Each of these pivots has in addition a head which is shown in Figure 3 for pivot 10b. In the embodiment of Figure 1 the heads of pivots 10, 10a and 10b serve the purpose of carrying the weight of sections 5, 5a and 5b, as shown in Figure 3. It is obvious, however, that in alternate embodiments the weight of the sections, or at least a part thereof, may be borne on saddle 2. Where this is done, it is advisable to substitute for channel 3 a metallic insert having overturned edges providing a metallic sliding surface parallel to the upper surface of the saddle. If this is done, the weight of the sections may be carried on broad flat washers like the bottom one shown in Figure 4. The bottom pivot should be kept short enough so that the weight of the section is not carried on its end. One disadvantage in supporting the sections on the saddle is that any lubricant which is employed is exposed on the upper surface of the saddle, whereas in the supporting arrangement shown in Figure 3, the lubricant is out of the way.

Figure 3 shows the guiding and section-carrying structure employed on the head-jamb. It includes a slotted block 12 which is screwed on to the top jamb. The slot in block 12 is wider than the heads of the pivots. Two metal straps, 13 and 14, are fastened to the lower surface of block 12 with their opposite edges extending beyond the vertical sides of the slot to define a guideway of slightly larger width than the diameters of the pivots, but considerably narrower than their heads. In the installation of a door, one of the straps, for example strap 14, may be put on after sections 5, 5a and 5b are placed in position with the heads of the upper pivots engaging the overhanging edge of strap 13.

It is apparent that the interlinkage employed herein necessitates a certain minimum amount of space between the top edges of the sections and the bottom surface of the head jamb. In the example shown herein, I employ an apron 15 which serves to close this space and to conceal the linkage mechanism, thus improving the door both functionally and artistically. The apron may comprise a facing strip 16 which nor-

mainly hangs in a vertical plane from the head casing by some suitable means, such as hinges 15a and a lip portion 17 fastened at the bottom edge thereof at right angles to it with its free edge formed to the overlap contour afforded by sections 6, 5, 5a and 5b in the closed condition of the door. The contour of the edge appears most clearly from Figure 2. When the door is opened one edge of each of the sections 5, 5a and 5b will be displaced outward from the axis of the guideway as appears in Figures 6 and 7. These edges will abut against the lip 17, pushing apron 15 outward to the position shown in Figure 2. If desired, light spring hinges may be employed to assure complete downward return of the apron when the door is again closed.

Figure 6 most clearly illustrates the operation of the interlinkage employed for communicating lateral displacement from one section to another, i. e., for causing all of the sections to be laterally displaced when one of them is moved by a force exerted on its handle and for turning them synchronously, i. e., maintaining them parallel to one another at all times. An anchor link 18 is fitted over pin 8 and also over a pin in the top edge of section 5, the last-mentioned pin being at an equal distance from pin 10 to the distance between the holes in anchor link 18. Two interconnecting links 19 and 20 have holes in their respective centers which are placed respectively over pivots 10 and 10a. One free end of link 19 is fitted over a pin in the unanchored edge of anchor section 6. This last-mentioned pin is so positioned that one-half of link 19, all of anchor link 18, and the top edges of anchor section 6 and section 5 define an equilateral parallelogram. The same arrangement is borne out sequentially along adjacent sections, as shown in the drawing, through to the final section which is 5b, in the present example. It is apparent that this assembly is flexible to movement in certain directions, due to the fact that the pivots are free to slide, and due to the fact that a parallelogram is a collapsible structure, for example, as contrasted with a triangle. If a force is exerted leftward on handle 21, as shown in Figure 6, this force will be communicated over several of the links and will be guided in the guideways respectively formed by U channel 3 and between straps 13 and 14, causing pivots 9, 9a, 9b, 10, 10a and 10b, and sections 5, 5a, and 5b to be displaced to the left in the guided direction. Since section 6 and link 18 are anchored and incapable of sliding to the left, each of the parallelograms will collapse with one of its diagonals becoming shortened and the other being lengthened whereby the surfaces of the sections, while always maintained parallel to each other, will be shifted away from the "closed" limiting position in which they are positioned edge-to-edge with their surfaces in alignment to an opposite "opened" limiting position where their surfaces are nested one above the other in a compact group to one side of the door opening as shown in Figure 7.

There appear in the drawing without assigned reference numerals such structural details as finish mouldings on the side jambs and beveled edges for the sections to provide an overlapping joint of satisfactory appearance. The moulding is desirable for sealing the edges of the door. The overlapping arrangement for adjacent edges of the sections is particularly advantageous when the folding closure-portion is used in a ceiling or roof section since, if sufficient pitch is given to the long axis of the guideways, an overlapping

roof structure is achieved in which water will run across the junctures between adjacent sections without leaking through.

Figure 8 illustrates how the edge pivots provided for the linkage arrangement may be appropriately offset from the center line between the surfaces of the sections so that in a fully closed condition of the door the front and back surfaces of all of the sections are respectively coextensive in two parallel planes. Portions of anchor link 18 and link 19 are cut away in Figure 8 to illustrate a suitable joint for abutting edges of adjacent sections to prevent a direct line of sight between them.

Where a folding closure portion of the kind described herein is employed in an opening of a ceiling or roof, no heads are required for any of the pivots inasmuch as the weight of the sections is borne on the sides of the pivots; rather than along their long axes. Accordingly, provision should be made that the pivots are strongly enough fastened to the sections and the guideways are strong enough to be capable of carrying the weight of the sections with the force exerted thereby being transverse to the axis of the pivots.

Where a folding door of the kind disclosed herein is employed for a garage and is opened and closed along a vertical axis the guideways serve primarily as guideways and do not support substantial weight. However, in such an embodiment the anchor section will support the weight of all of the sections and therefore, either its pivots should be designed accordingly, or they should be supplemented by hinges.

Figure 9 corresponds to Figure 3 but also shows a spiral spring which may be loaded so as to urge a section toward either its "opened" or closed position, as desired. In a garage-door embodiment there may be one spring 22 for each center pivot. Since the total number is quite large, and since each may be quite stiff, these springs may serve to counterbalance the weight of the sections. In Figure 9 the pivot is rotatably carried in a bearing in a lug 23 which is grooved on its opposite edges to fit into and be slidably borne in the guideway formed between straps 13 and 14. A spring-anchoring arm 24 holds the outside end of spiral spring 22 while its inside end is retained in the head of the pivot.

Where each spring 22 in its most unwound condition has a diameter greater than the thickness of one of the sections, it will be necessary, as shown in Fig. 10, to stagger the springs to prevent adjacent ones from interfering with each other. This can be accomplished if the heads of the pins comprising one alternate set thereof are of a first length and if the heads of all the others are either longer or shorter, so that adjacent springs may overlap.

The expression "folding-section portion for a closure" is used in the claims which follow as a way of broadly referring to folding-section "doors" for use in either walls, ceiling, or roofs.

What is claimed is:

1. A folding closure portion comprising: a plurality of parallel elongated sections; pantograph means interconnecting the sections along their end-edges; a pair of parallel guideways carrying the interconnected sections slidably therealong; said means comprising a set of links joined to the end-edges of the sections by center and end pivots in a lazy tong arrangement; one of the guideways including a support and two straps attached thereto with an edge of one in align-

ment with and spaced from an edge of the other; a plurality of lugs each having aligned grooves in a pair of its opposite edges and a bearing extending through its center portion between said edges; the lugs being borne in said one guideway with their grooves tightly engaging the aligned edges of said straps whereby they are only slidably movable in the guideway; the center pivot in each end-edge of each section extending through and being rotatably borne in the bearing of respective one of said lugs; and a spiral spring carried on the end of each of said last mentioned center pivots with its innermost turn fixed thereto, and its outermost turn fastened to the lug associated therewith, the springs being loaded to urge the sections along the guideways in the direction to fold the closure portion and to still be partially loaded when it is fully folded.

2. A folding closure portion as in claim 1 in which one of said two straps is removably attached to said support to facilitate installation of the folding closure portion in an opening.

3. A folding closure portion as in claim 1 in which the elongated sections are disposed horizontally and the guideways vertically and the two spiral springs of each individual section are pre-loaded fully to counter weigh the weight thereof.

4. A folding closure portion as in claim 1 in which said sections are disposed vertically within a four-sided frame with one of said lazy-tong arrangements also within the frame and along the top side thereof and which further comprises an apron adapted to hang down in a first position to cover the front of said lazy tong arrangement when the closure portion is unfolded and to be forced upward into a second position out of the way of interfering with said lazy-tong arrangement during folding of the closure portion, said apron including a facing strip pivotally attached along its upper edge to the top side of said frame to hang down in front of said

lazy-tong arrangement and a lip portion extending from the bottom edge of said facing strip toward said sections and having its free edge shaped to the contour presented thereby in their fully unfolded edge-to-edge relationship, said free edge of the lip portion facing the side-edges of the sections which move forward during folding of the closure portion to be forced thereby into said second position, and means yieldably urging said apron toward said first position.

5. A folding closure portion as in claim 1 in which a spring anchoring arm is attached to each of said lugs with its free end fastened to the outermost turn of a respective one of said springs.

6. A folding closure portion as in claim 1 in which the spiral springs for successive ones of said sections are positioned on the center pivots thereof at staggered distances from the ends of the sections whereby for the folded condition of the closure portion the springs of adjacent sections will tend to overlap rather than to abut against one another.
